UNITED STATES PATENT OFFICE.

ROLANDIS A. BLAIR, OF FORT WAYNE, INDIANA.

RAIL ANCHOR.

Application filed June 10, 1927, Serial No. 197,819. Renewed May 5, 1928.

My invention relates to rail anchors and has for its primary object the provision of a rail anchor of improved construction which, when applied to the base flange of a rail, 5 will exert a combination of several gripping actions thereon. A more specific object of the invention is to provide a rail anchor device adapted to be driven into frictional gripping engagement with one base flange 10 of the rail and which is so constructed that parts of the device are stressed during the application of the anchor to a rail and thereby tend to urge the rail gripping portions thereof toward a position to effect a shackle grip on the top and bottom surfaces of the rail.

Another object is to provide an anchor of the above character made up of two parts, either or both of which may be made from 20 flat metal blanks sheared from relatively narrow strips of stock material, and so engaged with each other that spring pressure of one member serves to hold the other in engagement with it when the anchor is free 25 of the rail, and thereby provide, in effect, a one-piece anchor. In this connection I contemplate, as one embodiment, the provision of a rail gripping member having jaws for engagement with the top and bottom surfaces 30 of one base flange and having an intermediate portion for exerting pressure upwardly against the bottom of the rail base, and to provide a transverse bar normally positioned between the rail base and the said 35 intermediate portion of the gripping member so as to be pressed against the bottom surface of the rail base by the resilience of the rail gripping member.

Another object is to provide an arrangement and construction of parts which will provide a convenient striking surface intermediate the rail gripping jaws, whereby the anchor, after the jaws are driven into tight gripping engagement with the rail, may be 45 slightly distorted by further driving operations so as to cause the transverse member of the device to snap over the opposite edge of the rail base.

A further object is to provide a device 50 of the above character which is so formed that the shackle grip of the jaw will not be loosened by the pressure of the jaw member against a cross tie, and which may be applied to either side of the rail in a position 55 to resist either forward or backward creeping movements of the rail.

The invention has for further objects such other new and improved constructions, arrangements, and combinations of parts, as will be hereinafter described and claimed 60 for carrying out the above stated objects and such other objects as will appear from the detailed description of the embodiments shown in the accompanying drawings.

In the drawings:

Fig. 1 is a side view of a rail anchor device constructed in accordance with my invention and is shown applied to a rail base.

Fig. 2 is an end view of the embodiment illustrated in Fig. 1 and illustrating the 70 manner in which the jaw member is distorted during the application of the anchor to a rail.

Fig. 3 is a view in perspective of the jaw member shown in Figs. 1 and 2.

Fig. 4 is a view in perspective of the transverse member employed in the embodiment shown in Fig. 1 to lock the jaw member in its applied position.

Figs. 5 and 6 are views similar to Figs. 1 and 2 but illustrating a modified construction.

Fig. 7 is a view in perspective illustrating the detailed construction of the jaw member as shown in Fig. 5.

Fig. 8 shows the cross bar employed in connection with the modification shown in Figs. 5 and 6.

Figs. 9 and 10 are views similar to Figs. 1 and 2, but illustrate a one-piece anchor 90 device.

Fig. 11 is a sectional view taken on line 11-11 of Fig. 9, looking upwardly toward the bottom surface of the rail base, and

Fig. 12 is a fragmentary view in perspective of the jaw end of the anchor illustrated in Fig. 9.

The embodiment of my invention shown in Figs. 1 to 4 inclusive, consists preferably of a rail gripping member 10 intended to 100 exert the major grip of the device on the rail, and a transverse member 11 which extends across beneath the rail base 12 and engages the opposite edge thereof so as to lock the gripping member 10 in its operative position on the rail. While the principal function of the bar 11 is to lock the gripping member on the rail, it exerts through its cooperation with the gripping member, a gripping action transversely of the rail and 110 also a substantial frictional grip on the bottom surface of said rail base.

The member 10 is made from a metal blank of uniform width and preferably, though not necessarily, of spring metal and is formed near its ends with recesses 13 and 14. The said recesses are formed so as to fit tightly one edge of the rail base. The blank is bent, to the configuration shown in Fig. 3, so as to provide spaced jaw portions 15 and 16 and an intermediate, upwardly projecting seat portion 17. The bends 18, 19, 20 and 21 are preferably formed with a relatively small radius so as to provide a construction that will be relatively rigid transversely of the rail, but which, nevertheless, will permit some slight flexing both longitudinally and transversely of the rail, when the member is being applied to the rail.

The transverse bar member is made preferably of steel and may, if desired, be of a higher or lower grade of steel than that used in the manufacture of the gripping member. The bar fits between the upstanding jaw portions 15 and 16 of the member 10 and is held in position by the spring action of said jaw portion exerted against the opposite edges of the bar. The downturned end 22 of the bar fits over the intermediate portion 17 of the member 10 and provides a face 23 which stands outwardly from the outer vertical edges of the jaw portions 15 and 16 and is adapted to receive the hammer blows during the application of the anchor to a rail. The other end of the bar is formed with an upturned flange 24 adapted to snap over the opposite edge of the rail base when the gripping member is driven to its operative position on the rail base. Preferably the length of the transverse bar is such that the edge 25 of the flange 24 will stand a slight distance under the lower edge 26 of the rail base when the jaws 15^a, 15^b and 16^a, 16^b have been driven to their operative positions, but which will be caused to snap over the edge of the rail as herein-after described, by the further driving operations.

The distance between the top surface 17^a of the intermediate portion 17 and the bottom surface of the rail base is normally less than the thickness of the transverse bar 11. With this arrangement of the bar, the upward movement of the jaws 15^a and 16^a on the inclined top surface of the rail base forces the upper surface 27 of the bar 11 into tight frictional engagement with the bottom surface of the rail base.

The gripping member and transverse bar are preferably assembled at the factory and shipped as a one-piece anchor. The anchor is applied to the rail by hooking the jaws 15^a and 16^a over one flange of the rail base and then striking the end face 23 of the bar until the jaws are driven into tight frictional engagement with the top and bottom

surfaces of the rail base and until the edge 25 of the bar snaps over the opposite edge of the rail base. The pressure exerted by the bar 11 against the bottom surface of the rail base, forces the intermediate portion 17 of the gripping member 10 downwardly. The downward pressure on the intermediate portion 17 effects a slight spreading of the lower end of the jaw portions 15 and 16 and thereby tilts the jaws from the dotted line position of Fig. 2 to the full line position. This distortion produces a shackle grip of the rail gripping jaws on the top and bottom surfaces of the rail base in addition to the prior frictional grip effected by the transverse movement of the jaws. When the jaws are driven to the limit of their movement, the edge 25 of the flange 24, as before stated, remains a slight distance inwardly from the lower edge 26 of the rail base. Further driving force applied to the end 23 of the bar 11 produces some compression of the metal of the inner face 28 of the flange 22 and also distorts the gripping member (presumably by slight spreading or unrolling of the bends 18 and 21) so as to produce, in effect, sufficient elongation of the bar 11 to permit the edge 25 of the flange 24 to snap over the edge of the rail base. By applying the anchor in this manner, the compression of the metal and the slight distortion of the member 10, for example by flexing the intermediate portion 17 from a position parallel to the edges of the jaws to a position at a slight angle thereto, takes up all looseness of the parts and provides a strong grip transversely of the rail. This grip is maintained by the tendency which the anchor member 10 has to return to the position from which it was sprung by the final driving force.

In Figs. 5 to 8 inclusive I have illustrated a modified embodiment. In this modification the transverse bar is of the same general form as the bar 11 in the previously described embodiment, but is somewhat shorter than the bar 11. The downturned end 31 of the bar 30, instead of extending over the outer edge of the intermediate portion 32 of the gripping member, fits into a slot 33 in the intermediate member. The fit of the flange 31 in the slot 33 is preferably a driving fit so as to avoid any looseness between the parts when the flange 34 of the bar snaps over the edge of the rail base. The gripping member designated generally by the reference character 35 is very similar to the gripping member shown in the previously described embodiment except that the bends 18^a-21^a, instead of being made normally along lines perpendicular to the longitudinal edges of the blank are bent along a line extending at an oblique angle to the said longitudinal edges so that the intermediate portion 32, when the gripping member is

formed, will extend outwardly at an angle to the outer vertical edges of the jaw portions as indicated by the reference character 35 in Fig. 5. This construction, it will be noted, provides a striking face which extends outwardly from the vertical edges 36, 37 of the jaw portions of the gripping member so that it can be struck independently of the other portions of the gripping member when the jaws have been driven to their full limit. The application of this modified embodiment and the character of grip effected are substantially the same as that described with the embodiment described in Figs. 1 to 4 inclusive and therefore need not be again described.

In Figs. 9 to 12 inclusive are shown another modified embodiment in which the principal features of the invention are embodied in a one-piece anchor device. The cross bar member 38 of this embodiment is made integral with the intermediate bearing portion 39 of the rail gripping jaw end portions 40 of the anchor. The rail gripping end 40 consists of spaced upstanding jaw portions 41-42, substantially the same as the jaw portions of the two preceding embodiments. The bends 43, 44, 45 and 46 are made with a somewhat greater radius than the similar bends of the other embodiments so as to provide greater resiliency in a direction transversely of the rail and to also form the intermediate portion of the gripping member with converging legs 47-48 which add to the resiliency of the gripping member vertically of the rail base. In this embodiment the top face 49 of the intermediate member 39 bears directly against the bottom surface of the rail base and is normally slightly above the lower jaws 50-51 when the anchor is free of the rail so that when the anchor is driven transversely of the rail base to force the lower jaws 50-51 and the upper jaws 52-53 into gripping engagement with the rail base, the downward pressure on the surface 49 will tend to spread the lower portion of the jaw portions 41-42 in a manner to effect a shackle grip of the rail gripping jaws on the top and bottom surfaces of the rail base, as illustrated in Fig. 10. The bends 43 and 46 are formed along lines extending at an angle to the longitudinal edges of the blank so that when the rail gripping end is bent to its completed form, the intermediate portion 39 will stand at an angle to the vertically disposed jaw portions 41-42 so as to provide a suitable striking surface 54. This embodiment of the invention is applied to the base flange of the rail in the same manner as the embodiments previously described by striking the edge 54. The driving force delivered against the intermediate portion of this embodiment and likewise the embodiment shown in Figs. 5 to 8 inclusive, tends to move

the outer edge of the intermediate portion into alignment with the outer edges of the vertically disposed jaw portions and thereby exerts an increased vertical pressure against the bottom surface of the rail base in addition to providing an effective elongation of the bar 38.

While I have illustrated my invention in three specific embodiments, it will be obvious that further modifications might be made without departure from the spirit of the invention. It will be understood therefore that I do not wish to limit myself to the specific construction herein shown and described except in so far as specific limitations may appear in the appended claims.

I claim:

1. In a rail anchor, a rail gripping member provided with a jaw portion having gripping surfaces for engaging one flange of a rail base and provided with a portion arranged to exert pressure against the bottom of the rail and so disposed with relation to the said gripping surfaces as to be flexed transversely of the rail and depressed from its normal position during the application of the device to a rail.

2. In a rail anchor, a rail gripping member provided with a relatively rigid jaw portion having gripping surfaces for engaging one flange of a rail base and provided with a portion arranged to exert pressure against the bottom of the rail and so disposed with relation to the said gripping surfaces as to be depressed from its normal position during the application of the device to a rail, and means movable transversely of the said jaw portion, for locking the gripping member in its upright position.

3. In a rail anchor, a rail gripping member provided with spaced jaw portions having gripping surfaces for engaging one flange of a rail base and provided with a portion arranged between said jaw portions and so disposed with relation to said gripping surfaces as to be depressed from its normal position during the application of the device to a rail, and separate means engaging the opposite edge of the rail base for locking the rail gripping member in its applied position.

4. In a rail anchor, a rail gripping member provided with spaced jaw portions having gripping surfaces for engaging one flange of a rail base and provided with a portion arranged between said jaw portions and so disposed with relation to said gripping surfaces as to be depressed from its normal position during the application of the device to a rail and means interposed between said intermediate portion of the gripping member and the bottom surface of the rail and engaging the opposite edge of the rail base to lock said gripping member in its applied position.

5. In a rail anchor, a rail gripping member formed with spaced jaw portions having gripping surfaces adapted to be driven into gripping engagement with one flange of the rail base and formed with an intermediate portion extending upwardly toward the bottom surface of the rail base, and a transverse bar positioned between the bottom surface of the rail base and said intermediate portion and adapted to engage the opposite edge of the rail base; the distance between the intermediate portion and the bottom surface of the said base being normally less than the thickness of the bar, whereby the said intermediate portion is depressed in applying the anchor to a rail. 65
6. In a rail anchor, a rail gripping member formed with spaced jaw portions arranged edgewise with respect to the rail and having gripping surfaces adapted to be driven into gripping engagement with one flange of a rail base and formed with an intermediate portion extending upwardly toward the bottom surface of the rail base, 70 and a transverse bar positioned between the bottom surface of the rail base and said intermediate portion, formed at one end with a downturned flange for engagement with the outer edge of said intermediate portion and at the other end with an upturned flange for engagement with the opposite edge of the rail base; the distance between the intermediate portion and the bottom surface of said base being normally less than the thickness of the bar, whereby 75 said intermediate portion is depressed in applying the anchor to a rail. 80
7. In a rail anchor, a rail gripping member provided with spaced jaw portions having gripping surfaces for engagement with one flange of a rail base and provided intermediate said jaw portions with an upwardly projecting portion normally so disposed with respect to said gripping surfaces 85 as to be depressed in applying the anchor to a rail, whereby the depression of said intermediate portion moves the jaw portion into shackle gripping engagement with the rail base. 90
8. A rail anchor, a rail gripping member provided with spaced jaw portions having gripping surfaces for engagement with the top and bottom surfaces of one flange of a rail base and provided intermediate said jaw portions with an upwardly projecting portion normally so disposed with respect to said gripping surfaces as to be depressed in applying the anchor to a rail, whereby the depression of said intermediate portion 95 spreads apart the lower ends of said jaw portions and thereby exerts a shackle gripping force on the top and bottom surfaces of the rail base. 100
9. In a rail anchor, a rail gripping member provided with spaced jaw portions having gripping surfaces for engagement with the top and bottom surfaces of one flange of a rail base and provided intermediate said jaw portions with an upwardly projecting portion normally so disposed with respect to said gripping surfaces as to be depressed in applying the anchor to a rail, whereby the depression of said intermediate portion spreads apart the lower ends of the jaw portions and thereby exerts a shackle gripping force on the top and bottom surfaces of the rail base, and a bar engaging the gripping member and the opposite edge of the rail to maintain the gripping member in its operative position on said base flange. 105
10. In a rail anchor, a rail gripping member provided with spaced jaw portions having gripping surfaces for engagement with one flange of a rail base and provided intermediate said jaw portions with an upwardly projecting portion normally so disposed with respect to said gripping surfaces as to be depressed in applying the anchor to a rail, whereby the depression of said intermediate portion spreads apart the lower ends of said 110 jaw portions and thereby exerts a shackle gripping force on the top and bottom surfaces of the rail base, and a bar formed on one end with a flange for engaging the gripping member and providing a surface which extends beyond the outer edges of the jaw portions and formed on the other end with a flange for engagement with the opposite edge of the rail base to lock the gripping member in its applied position. 115
11. A rail anchor comprising a rail gripping member formed with spaced jaw portions for engagement with one flange of a rail base, and a transverse bar engaging the opposite edge of the rail base and held in engagement with the gripping member by the resilience of said jaw portions. 120
12. A rail anchor comprising a rail gripping member and a separately formed bar held at one end by a spring grip exerted by said gripping member and formed at the other end with means for engagement with the opposite edge of the rail base. 125
13. A rail anchor comprising a rail gripping member and a separately formed bar held at one end by a spring pressure exerted by said gripping member and formed at the other end with means for engagement with the opposite edge of the rail base; the end of the said bar engaging said gripping member being formed with a downturned portion which extends outwardly from the rail gripping member to provide a striking surface adapted to receive the hammer blows during the application of a device to a rail. 130
14. A rail anchor comprising a member provided with spaced jaw portions for engaging one flange of a rail and an inter-

- mediate portion extending under the base of the rail, a transverse bar for engagement with the opposite edge of the rail base supported on said intermediate portion of the gripping member and retained in its normal position by a spring pressure exerted by said jaw portions.
15. A rail anchor comprising a member provided with spaced jaw portions for engaging one flange of a rail and an intermediate portion extending under the base of the rail, a transverse bar for engagement with the opposite edge of the rail base supported on said intermediate portion and retained in position thereon by spring pressure exerted by said jaw portions; the length of said bar being normally insufficient to clear the opposite edge of the rail base when the jaw portions have reached the limit of their applying movement, whereby it is necessary in applying the device to a rail to distort the gripping member in a direction transversely of the rail to effect engagement of said bar with the opposite edge of the rail base.
25. 16. A rail anchor comprising a member provided with spaced jaw portions for engaging one flange of a rail and an intermediate portion extending under the base of a rail, a transverse bar for engagement with the opposite edge of the rail base and the said intermediate portion and retained in position by a spring pressure exerted by said jaw portions, the length of said bar being normally insufficient to clear the opposite edge of the rail base when the jaw portions have reached the limit of their applying movement, whereby it is necessary to compress the metal of the co-engaging surfaces of said members to effect engagement of the bar with the opposite edge of the rail base.
35. 17. A rail anchor comprising a rail gripping member formed with spaced jaws for engagement with one flange of a rail base and provided with an upwardly extending intermediate portion adapted to be depressed during the application of the gripping member to its operative position and thereby effect a spreading of the lower end of said gripping members to produce a shackle grip of said jaw portions on the top and bottom surfaces of the rail base, a transverse bar positioned between said jaw portions and adapted to be clamped between the bottom surface of the rail base and said intermediate portion of the gripping member during the application of the anchor to a rail; the length of said bar being normally insufficient to engage the opposite edge of the rail base when the jaw portions have been driven to the full limit of their movement, whereby the engagement of said bar with the opposite edge of the rail base is effected by compression of the co-engaging surfaces of said bar and said gripping mem-
- ber and by distortion of said gripping member transversely of the rail.
18. In a rail anchor, a rail gripping member provided with spaced jaw portions having gripping surfaces for engagement with one flange of a rail base and provided intermediate said jaw portions with means for exerting pressure vertically of the rail, a separable transverse bar engaging said intermediate portion and formed to engage the opposite edge of the rail base.
19. In a rail anchor, a rail gripping member provided with spaced jaw portions having gripping surfaces for engagement with one flange of a rail base and provided with an intermediate upwardly projecting portion, a transverse bar engaging said intermediate portion and movable relatively to said jaw portion during the application of the anchor to a rail and formed to engage a longitudinal edge of the rail base to maintain said jaw portions in gripping position on the rail.
20. In a rail anchor, a rail gripping member provided with spaced jaw portions having gripping surfaces for engagement with one flange of a rail base and provided intermediate said jaw portions with an upwardly projecting portion, a transverse bar engaging said intermediate portion and formed to engage a longitudinal edge of the rail base; the length of said bar being normally insufficient to engage said edge of the rail base and the said upwardly projecting portion of the gripping member being adapted to yield transversely of the rail to permit engagement of said bar with the said longitudinal edge of the rail base.
21. In a rail anchor, a gripping member for gripping one edge of the rail base, separable means engaging said gripping member and adapted, by a flexing of said gripping member transversely of the rail, to engage the other edge of the rail base to lock said gripping member in its operative position.
22. A rail anchor comprising a relatively rigid jaw portion for gripping the top and bottom of a rail base at one side of the rail and having a yielding part, and a retaining member carried by said yielding part and movable transversely of the rail relative to said jaw portion into gripping engagement with the opposite edge of the rail base to lock the jaw portion in its rail gripping position.
23. A rail anchor comprising a jaw portion having a rail gripping part and a portion movable both vertically and transversely of the rail relative to said first mentioned part and adapted by said movement to so stress a portion of the anchor as to exert spring pressure against the rail.

ROLANDIS A. BLAIR.
